UNITED STATES PATENT OFFICE.

FRANK H. JOHNSTON, OF CHICAGO, ILLINOIS, ASSIGNOR, BY MESNE ASSIGNMENTS, TO ACME CARD SYSTEM COMPANY, OF CHICAGO, ILLINOIS, A CORPORATION OF ILLINOIS.

VISIBLE-CARD SYSTEM.

Application filed May 24, 1922, Serial No. 563,237. Renewed January 14, 1926.

This invention relates to improvements in visible card systems and refers more particularly to a protective sheath or strip which is positioned along the lower or exposed edge of the card to prevent wearing or dog-earing of the cards, and further, keeping the edges of the cards clean and the identifying or printing data thereon plainly legible.

Among the salient objects of the invention are to provide a card holder in which index cards may be removably placed and held in position upon a card support; to provide a construction in which both the protective strip and card may be easily removed from the card holder and replaced quickly after the entries have been placed upon the cards, or a new card put in place.

Fig. 1 is a fragmentary face view of a portion of the frame with the overlapping cards in position on the hangers.

Fig. 2 is an enlarged detail of one corner of the card holder with the protective strip and corner of the card showing.

Fig. 3 is an edge view of the construction shown in Fig. 2.

Fig. 4 is a view showing a corner of the card holder and the fastening wire or staple for holding the protective strip and card.

Fig. 5 is a modified form of construction with the protective strip and card in place.

Fig. 6 is a detailed view showing the construction used in Fig. 5 with the card and protective strip removed.

Fig. 7 is a further modification in which a tape strip is used for the fastening or card supporting element.

Fig. 8 is a view of the modified form shown in Fig. 7 with the card and protective strip removed.

Referring to the drawing, a frame 1 has along its lateral edges channels 2 behind which are held the flexible wire hangers 3. These hangers support card holders 4 by means of the hinge clips 5, the latter being removably attached to the cards which form the bodies of the card holders and formed with the cylindrical holes in the upper portions by means of which they are threaded upon the ends of the hangers 3. The card

holders may be removed from the hangers by merely bending them centrally, thus shortening the length of the cards so that the hinges may be slid from the hangers.

The card holder 4 has near its upper edge

a curved slit 4^a, which serves to provide an overlapping tongue engaging the top of the index card 6 which it overlaps and assists in holding in place. On the lateral edges of the card holder near the lower edge, are cut slots 4^b in which are placed the staples 7 which extend diagonally from the slots to the bottom edge of the card holders and which have their legs 7^a bent along the back surface of the card holder, the extremities 7^b piercing the card holders and being turned back to clinch the staples fixedly thereto. These staples being positioned on the lateral edges of the card holders diagonally across their lower corners, serve to hold the protective strip 8 in position by engaging the slots 8^a cut into the ends of the protective strips.

These protective strips may be of any desired material, those shown in the drawing being preferably of transparent or translucent substance such as celluloid, pyrolin or the like, either white or colored as desired.

In Fig. 1, the card 6 is shown in place on the card holder 4 with the overlapping tongue of the card holder in 4^a engaging its upper edge and being supported by the staples 7 on its lower edge. The protective strips cover the lower or exposed edges of the card and prevent the soiling of the cards from continuous use, and materially lengthen the life of the cards, as the strips are made of more durable substance and they withstand use for a considerably greater period of time. This construction also permits the removal and replacement of the cards by simply withdrawing the cards from the upper and overlapping tongue and raising it from the engagement with the supporting staples 7. The card shown in Fig. 1 and used in connection with the retaining staples and protective strip shown in Fig. 2 and Fig. 4 would necessarily be of somewhat smaller size than the card holder 4, due to the fact that the slots 4^b are of considerable depth, and the cards to fit between the staples must necessarily be somewhat shorter than the card-holding portion 4.

In the modified form of construction, that shown in Figs. 5 and 6, the staples are fastened or attached to the cards diagonally across the corners of the card holders so that a normal size card or a card substan-

tially the same size as the card holder may be used. In such a construction it is only necessary to slot the protective strip as shown at 8b in order to hold the strips in place and prevent their removal with the cards.

A very similar type of construction is shown in the modified form in Figs. 7 and 8. Here, instead of using the metal staples such as shown at 7 in the former figures, a fabric or durable paper strip 9 may be glued diagonally across the corner of the card holders to support the cards in a similar manner as that explained in connection with the metallic staples. The protective strips in this type of construction will necessarily be shouldered as shown at 8c in order to engage the lower edges of the strips to be held in position.

A further feature of the single-ply protective strip used in connection with the overlapping visible card system is the fact that there is no pocket formed about the lower edges of the cards to collect dirt and dust and not only soil the cards, but obliterate the identifying data which is printed upon the visible portion of the index card.

This construction also has the added advantage of being easily removable and readily replaced by new strips and cards, and the entire construction in addition to its simplicity is light and easily handled by the operator.

I claim as my invention:

1. In a visible card system, the combination with a frame of a plurality of overlapping card holders mounted on said frame, said holders comprising diagonally positioned retaining members and protective strips engaged by the retaining members and covering the exposed edges of cards in the card holders.

2. In a visible card system, the combination with a frame of a plurality of overlapping card holders mounted on said frame, said holders comprising retaining members

fastened to the lower corners of the card holders, cards supported by said retaining members, and protective strips removably supported by the retaining members and substantially covering the exposed portions of cards in the card holders.

3. In a visible card system, the combination with a frame of a plurality of overlapping card holders mounted on said frame, said holders comprising retaining members fastened adjacent the lower corners of the card holders, cards supported by said retaining members, and single-ply protective strips of a transparent substance removably positioned behind the retaining members and substantially covering the exposed portions of cards in the card holders.

4. In a visible card system, the combination with a frame, of a plurality of overlapping card holders hinged to said frame, and comprising retaining members fastened adjacent the corners of the card holders, cards removably positioned in said holders, and protective strips removably positioned behind the retaining members and covering the exposed edges of the cards.

5. In a visible card system, the combination with a frame, of a plurality of overlapping card holders hinged to said frame, and comprising retaining members fastened across the corners of the card holders, cards removably positioned in said holders, and protective strips removably positioned behind the retaining members covering the exposed edges of the cards, said retaining members preventing the removal of the protective strips with the removal of the cards.

6. In a visible card system, the combination with a frame, of a plurality of overlapping card holders hinged to said frame, and comprising card retaining members across the lower corners of the card holders and a member adapted to overlap the upper edge of the card and index cards removably carried by said card holders.

FRANK H. JOHNSTON.
